UNITED STATES PATENT OFFICE.

WILLIAM H. LEININGER, OF SALEM, OREGON.

AMALGAMATOR.

SPECIFICATION forming part of Letters Patent No. 267,907, dated November 21, 1882.

Application filed August 2, 1882. (No model.)

To all whom it may concern:

Be it known that I, WILLIAM H. LEININGER, of Salem, in the county of Marion and State of Oregon, have invented a new and Improved 5 Amalgamator, of which the following is a full, clear, and exact description.

The object of my invention is to facilitate obtaining the gold contained in the sand of the beach and the bottom of the sea.

10. The invention consists in a device to which a series of amalgamated plates are attached, which device is drawn through the auriferous sand, which is thereby stirred and raised, so that it passes between these plates, the gold 15 being retained on these plates.

Reference is to be had to the accompanying drawings, forming a part of this specification, in which similar letters of reference indicate corresponding parts in both the figures.

20. Figure 1 is a plan view of my improved amalgamator. Fig. 2 is a longitudinal elevation of the same.

A series of harrow-teeth, A, preferably of shovel pattern, are attached to the cross-bars 25 of a frame, B, made of any suitable material. The agitators or teeth can be made of any desired suitable metal. A frame, H, is held above the frame B by means of short posts F. Amalgamated silver or silver-plated copper plates 30 C are secured transversely and horizontally on the frames B and H, the plates on the lower frame, B, being slightly in advance of the plate C on the upper frame, H. The said plates are preferably provided with ruffles or corruga-

tions, or are checkered, as shown, so that they 35 will more readily hold the amalgam.

The device is operated by means of a steam-tug in deep water, or by a horse or some other suitable power on the beach or in shallow water. Thereby the auriferous sand is stirred 40 and raised, and passes over and between the plates C, on which the gold contained in the sand is retained, the sand pressing through between the plates.

Having thus fully described my invention, I 45 claim as new and desire to secure by Letters Patent—

1. An amalgamator made substantially as herein shown and described, and consisting of a device provided with a series of amalgamated plates or devices and teeth or agitators, and suitable propelling means, as set forth.

2. In an amalgamator, the combination, with the frame B, of the agitators or teeth A and the amalgamated plates C, attached to the frame B, and suitable propelling means, substantially as herein shown and described, and for the purpose set forth.

3. In an amalgamator, the combination, with the frames B and H, of the agitators or teeth A and the amalgamated plates C, secured on the frames B and H, and suitable propelling means, substantially as herein shown and described, and for the purpose set forth.

WILLIAM H. LEININGER.
